UNITED STATES PATENT OFFICE.

VICTOR G. VAUGHAN, OF MANSFIELD, OHIO, ASSIGNOR TO WESTINGHOUSE ELECTRIC & MANUFACTURING COMPANY, A CORPORATION OF PENNSYLVANIA.

ELECTRIC AIR HEATER.

Application filed June 4, 1927. Serial No. 196,482.

My invention relates to electrical heaters and particularly to automobile engine heaters.

An object of my invention is to provide a relatively simple and compact automobile engine heater that shall embody a minimum number of parts and that shall permit of being easily and quickly assembled.

In practicing my invention, I provide a tubular casing having a centrally apertured end cap at one end thereof, a refractory resistor-supporting member extending through the apertured end cap and clamped in proper operative position by an expanded collar and by an end cover member secured against the end cap.

The single figure of the drawing illustrates a device embodying my invention, shown in side elevation, with a portion thereof shown in section.

A heater designated generally by the numeral 11 comprises a perforated tubular casing 12, a substantially closed end cap 13, a centrally apertured end cap 14, and an end cover 15. The tubular casing portion 12 may be perforated in any suitable or desired manner, and is shown as being provided with a plurality of circular openings 16 and square or lozenge shaped openings 17. While I have illustrated only a few of these respective perforations, it is to be understood that the entire surface of the casing 12 is provided with such openings.

The end cap 13 is substantially solid and of dish shape, and is secured to one end of the casing 12 by any suitable means, such as spot welding. A hook member 18 is provided, which may also be secured to the casing 12 by spot welding.

The end cap 14 is also of dish shape and the peripheral portion thereof may be spot welded to the other end of the casing 12. It is provided with a central aperture 19, the walls of which are punched outwardly to constitute a peripheral flange portion 21.

A heating unit is located within the casing 12 and comprises a single refractory resistor-supporting member 22 having a reduced end portion, which is provided with a helically extending groove 23 in the surface thereof for receiving a resistor member 24 which comprises a helically wound resistor wire.

One end portion of the resistor-supporting

member 22 is made in the form of an expanded collar 25 to provide a shoulder 26 which is in operative engagement with the outer edge portion of the flange 21. The end cover member 15 is of substantially cone shape, as is shown in the drawing, and is of such dimensions both laterally and longitudinally of the heater as to tightly clamp the refractory resistor supporting member 22 in its proper operative position, as shown in the drawing, with the shoulder portion 26 against the edge of the flange 21 and with the outer end of the collar wedged within the cover member 15. A plurality of sheet metal screws 27 extend through the peripheral portion of the cover 15 and through the end cap 14 to securely hold the cover member in its proper operative position against the cap, and to thereby securely clamp the refractory member in its proper operative position and hold it coaxially with the casing 12.

Terminal members are provided on the refractory resistor supporting member 22 at the end of the collar portion 25, which terminal members may comprise machine screws 28 and 29 to which the respective terminals of the resistor 24 may be connected and to which may also be connected the twin conductors of a conductor cord 31, of the usual type. The conductor cord 31 has a knot 32 tied therein close to the inner end thereof, and a perforated disc 33 of a suitable electric-insulating material is located thereon and may engage a bushing 34 of electric-insulating material which is located within an end opening in the cover member 15, and through which the cord 31 extends. A screw connecting plug 35 is mounted on the other end of the conductor cord 31 to permit of connecting the heater to a suitable source of supply of electric energy.

The refractory resistor-supporting member 22 is a unitary member and has the resistor wire wound thereon, and the terminals thereof connected to the terminal members 28 and 29 before the member 22 is located within the casing. If the conductor cord is attached thereto, the disc 33 may be mounted thereon, before the plug 35 is secured to the cord, after which the cord may be pushed through the bushing 34 located in the cover member 15, which cover member may then be located in its proper operative position against the end cap 14 and secured thereagainst by the sheet metal screws 27.

The device embodying my invention thus provides a relatively simple and compact air heater embodying a minimum number of parts that may be easily and quickly assembled.

Various modifications may be made in the device embodying my invention without departing from the spirit and scope thereof, and I desire, therefore, that only such limitations shall be placed thereon as are imposed by the prior art or are set forth in the appended claim.

I claim as my invention:

In an air heater, in combination, a casing, an apertured end cap therefor, a refractory-supporting member having one portion extending through the aperture into the casing

and an expanded end portion of larger diameter than the aperture of said end cap located outside the casing, an end cover member of cup-shape invertedly presented to said apertured end cap, said cover member being provided with a seat to receive the expanded end portion of the resistor-supporting member, and means for securing the end cover member to the end cap whereby the expanded end portion of the resistor-supporting member is clamped between the end cap and the cover member to hold the supporting member firmly in place.

In testimony whereof, I have hereunto subscribed my name this 10th day of May, 1927.

VICTOR G. VAUGHAN.
